ELECTRIC LANTERNS

Richard William Stevens, London, England

Application June 28, 1955, Serial No. 518,605

Claims priority, application Great Britain June 29, 1954

1 Claim. (Cl. 240—25)

The present invention relates to electric lanterns for use with elongated electric lamps, such for example as fluorescent lamps or sodium lamps.

It has for its object to provide an improved lantern, suitable for street lighting which enables a satisfactory light distribution to be obtained from a light source of the type which is extended in at least the vertical direction. Examples of such sources, which are also extended in one horizontal dimension, are a small plurality of fluorescent tubes arranged one above the other or a U-shaped sodium lamp arranged with the limbs of the U one above the other. The type of distribution required is one in which a minimum of light is directed above the horizontal, a peak intensity is provided between 10° and 20° below the horizontal, and the intensity falls off steadily to a still appreciable value as the direction approaches the downward vertical. The arrangement of lamps one vertically above another has the advantage that the amount of re-direction of light that has to be effected by the lantern in order to produce the required distribution is less than with other arrangements. Thus with three fluorescent lamps one above the other, the light intensity emerging directly from the lamps in a downward direction is substantially that of one lamp while that available laterally is that of three lamps.

It is usually desirable that only light emitted above the horizontal be re-directed by the light control system, since the desired luminous intensities in directions below the horizontal are usually greater than the intensities provided by the source in these directions. The control system is designed to provide the balance. It follows therefore, that the control system will usually be arranged to extend upwards from a position approximately level with the upper part of the source.

Control may be achieved by re-directing the light by refraction or reflection. In the latter case it is difficult to arrange for the reflectors to intercept an adequate amount of light. In the former case, the control system often consists of a transparent panel having, on one or both sides, a number of prisms running parallel to the axis of the source. The difficulty mentioned above as met with reflecting systems does not arise, but there is another difficulty which it is the purpose of this invention to overcome. This is that, when the source is of the type specified having substantial vertical depth, and when the prisms are all of the refraction type, if light from the upper part of the source is directed into the main beam, i.e. in the direction of maximum intensity at 10 to 12 degrees below the horizontal, then the light from the lower parts of the source tends to be directed above the main beam. On the other hand, the amount of light from the lower part of the source intercepted by the refractor panel, is often relatively small and losses are high due to the large angles of incidence involved, so that if the panel is designed to direct light from this part into the main beam, the system is rather inefficient.

2

even if the light from the rest of the source is directed below the main beam.

According to the present invention a lantern for use with a light source of the type set forth comprises a refractor panel including prisms running horizontally, at least the upper prisms, and preferably all or nearly all the prisms, being adapted to direct light from the light source by total internal reflection at one face and by refraction. The prisms may be arranged in a plurality of horizontal zones, the prisms in each zone being like, and the prisms in different zones differing suitably in shape from one another. The prisms in the lowest zone may be purely refracting prisms. The inwardly-directed bases of the prisms in one or more upper zones are preferably inclined inward and upward relatively to those of the prisms in one or more lower zones. With such a panel, if light from the upper part of the source is directed into the main beam, light from the other parts can be arranged to be directed below it.

20 The invention is of particular value where the light source is of large dimensions relatively to the panel, or more precisely where, measured in a vertical plane, the ratio of the distance along a line between the centre of the panel and the centre of the light source to the dimension of the light source between planes parallel to the said line is 3 or less.

30 The terms "horizontal" and "vertical" are used in this specification for clearness and simplicity in order to define the relationship between the dimensions of the source and the refractor panel and it is to be understood that the lantern according to the invention may be used with the prisms running other than horizontally.

35 The invention will be described by way of example with reference to the accompanying diagrammatic drawings in which:

Fig. 1 shows the relative dispositions of a lantern according to the invention and three fluorescent tubes to be used therewith,

40 Fig. 2 is a view of the inside of one of the panels in Fig. 1,

Fig. 3 is an enlarged sectional view of the lower left hand corner of the lantern in Fig. 1,

45 Fig. 4 is a much enlarged view showing the shapes of the prisms used in each of the five zones 1 to 5 in Fig. 1, the prisms in Fig. 4 being correspondingly numbered, and indicates typical light paths, and

50 Fig. 5 shows a preferred modification of the lantern of Fig. 1 for use with a sodium lamp.

Referring to Figs. 1 to 4, the lantern has two panels 10 and 11 of "Perspex" (registered trademark) about 8½ inches apart and is of rectangular shape with rounded corners. Each panel measures 18 inches x 4½ inches vertical depth. The prisms are in five zones (1 to 5 in Fig. 1) in each of the two panels, the vertical depths of the zones 1 and 2 being approximately equal and these two zones extending over approximately half the vertical depth of the panel. Zones 3 and 4 are of approximately equal depth and zone 5 has a depth which is about a half of that of the zone 4. The bases 12 of the prisms in the two upper zones 1 and 2 of each panel lie in a plane inclined inward and upward at 10° to the vertical. The bases 13 of the prisms in the three lowest zones 3, 4 and 5 of each panel lie in a plane inclined downward and inward at an angle of 5° to the vertical.

65 As shown in Fig. 4, the upper surfaces 14 of all the prisms in the upper four zones are arranged to reflect the light falling on them from the source. These surfaces are inclined downward and outward at angles of 1°, 6°, 12° and 12° respectively proceeding from the uppermost prism downward. Downward and upward inclinations are of course with respect to the horizontal.

The prisms in the two upper zones 1 and 2 have each only one further surface, namely the lower surface 15 through which light is passed after reflection at the upper surface, the light being refracted in passing through the lower surface. These lower surfaces are inclined upward and outward at 29.5° and 22.2° respectively in the zones 1 and 2. The prisms in zones 3 and 4 each have two mutually-inclined lower surfaces 16 and 17 through the outer one 16 of which light reflected from the upper surface 14 passes and is refracted. The lower surfaces 17 nearer the centre of the lantern in both zones are inclined upward and outward at 2°. The surfaces 16 in zones 3 and 4 are shorter than the surfaces 17 and are inclined upward and outward at 25.6° and 38.7° respectively.

The refracting prisms in the lowest zone 5 have upper surfaces 18 inclined downward and outward at 55.1° and lower surfaces 19 inclined upward and outward at 21°.

The overall thickness of the walls of the panels to the apices of the prisms is about $\frac{3}{16}$ inch, the prisms themselves occupying about half of this thickness. The vertical depths of the bases of the prisms are about equal for zones 2, 3 and 4, rather larger for zone 1 and about three times as large as zone 2 in zone 5. The bases abut against one another.

The light source shown in Fig. 1 is in the form of say three fluorescent tubes 20, 21 and 22 arranged one vertically above the others and is arranged symmetrically in the lantern with the plane 23 through the upper surface of the source (the upper wall of the upper fluorescent tube 20) and the lower edge of the panel 11 making an angle of about 15° to the horizontal; the said surface being, as shown, above the said edge.

It will be seen in Fig. 1 that the ratio of the distance along the line 25 between the centre of the panel 10 and the centre of the light source to the dimension 26 of the light source between planes 27 and 28 parallel to the line 25 is large. This ratio is conveniently made about 2.

With a sodium lamp 24 the positions of the refractor panels 10 and 11 can advantageously be modified as indicated in Fig. 5 to increase the areas of the prism-bases as seen from the light source. It is a feature of the form of panel described that it is possible to do this without altering the direction of the main beam. Thus it may be done, as shown, by arranging the bases of the prisms in the lowest three zones to be vertical and therefore inclining the bases of the prisms in the first two zones at 15° instead of 10° to the vertical as previously described,

and arranging the outer surfaces of the panels at 5° to the vertical, the remainder of the design being the same as described with reference to Figs. 1 to 4.

In either embodiment a diffusing reflector may be arranged within the lantern above the uppermost lamp to prevent emission of light upward and to increase the light emitted downward.

Whilst the invention has been described with particular reference to a horizontally disposed light source, it is to be understood that it may be applied equally well to a short source of small horizontal dimensions and extended only in the vertical direction. The refractor may then be of circular cross-section with its axis coinciding with that of the source and the prisms are then arranged to extend circumferentially.

15 I claim:

A lighting fixture comprising a refractor panel having a vertical array of horizontal prisms arranged in an upper group and a lower group, the upper group of prisms in said vertical array having their bases in a plane inclined inwardly and upwardly to direct light by total internal reflection at one face and by refraction, the lower group of prisms having their bases in a plane inclined inwardly and downwardly and a vertical array of tubular electric discharge lamps, each lamp being substantially horizontal, and only one of the lamps in said plurality being in the same horizontal plane as any of said prisms, but all of said lamps being positioned with respect to said refractor panel so that at least part of the upward light from each lamp will be redirected downwardly by said prisms whereby the lamps emit most of the direct light in a lateral direction and the upward component of light above each lamp is reflected down by said prisms.
